[57] CLAIM

The ornamental design for the electrical outlet unit, as shown and described.

DESCRIPTION

FIG. 1 is a perspective view of an electrical outlet unit according to the invention;

FIG. 2 is a rear view of the electrical outlet unit of FIG. 1; FIG. 3 is a side view of the electrical outlet unit of FIG. 1, both sides being identical;

FIG. 4 is an end view of the electrical outlet unit of FIG. 1, both ends being identical;

FIG. 5 is a front view of the electrical outlet unit of FIG. 1; FIG. 6 is a perspective view of an alternative embodiment of an electrical output unit according to the invention, wherein the front panel includes a translucent portion; and, FIG. 7 is a perspective view of an alternative embodiment of an electrical outlet unit according to the invention, wherein one of the side panels includes a translucent portion.

All other views of the alternative embodiments are the same as FIGS. 1 through 5 except as stated;

The broken line showing is included for the purpose of illustrating environmental structure only and forms no part of the claimed design;
